United States Patent Office.

A. J. PRESCOTT, OF CATAWISSA, PENNSYLVANIA.

Letters Patent No. 96,035, dated October 19, 1869.

IMPROVED REAMER.

The Schedule referred to in these Letters Patent and making part of the same.

To all whom it may concern:

Be it known that I, A. J. PRESCOTT, of Catawissa, in the county of Columbia, and in the State of Pennsylvania, have invented certain new and useful Improvements in Reamers; and do hereby declare that the following is a full, clear, and exact description thereof, reference being had to the accompanying drawings, and to the letters of reference marked thereon, making a part of this specification.

The nature of my invention consists in the construction of an outside reamer, provided with cutting-parts and blank, or smooth parts, and is so constructed that it will not chatter while at work, and also leaves the work smooth.

In order to enable others skilled in the art to which my invention appertains to make and use the same, I will now proceed to describe its construction and operation, referring to the annexed drawings, in which—

Figure 1 is a side elevation of the reamer, and

Figure 2 is an end view of the same.

A represents the hollow head of the reamer, which is secured to the end of the handle B, the pin F.

The end of the hollow head A, upon the inside, is balled or tapered out, and is provided with one or more cutting-parts C C, and one or more blank or smooth parts D D, which serve to steady the reamer and keep

it from chattering while at work; also, smooth the work, and keep the dirt and chips off the same.

The open spaces 1, 2, 3, 4, are for the purpose of breaking the line of centre to allow the reamer to cut, also to allow the chips and dirt to escape, and to destroy friction while the reamer is revolving.

The edges G G of the blank or smooth parts D D are cutting-edges, to true up any imperfection there may be from the cutting-sides C C.

The hollow in the head H is for the purpose of allowing the work to run in, if required, while the holes i i in the head allow any dirt or chips that might get in there to escape.

Having thus fully described my invention,

What I claim as new, and desire to secure by Letters Patent, is—

An outside ball or taper-reamer, having a hollow head, H, one or more cutting-sides C, one or more blank or smooth sides D, with cutting-edges G, open spaces 1, 2, 3, 4, and holes i i, all substantially as and for the purposes herein set forth.

In testimony that I claim the foregoing, I have hereunto set my hand, this 30th day of August, 1869.

Witnesses:

A. J. PRESCOTT.
